METHOD OF MAKING SLIDE FASTENER
STOPSMax Kiessling and Adolph Krieger, Waterbury,
Conn.Application October 23, 1936, Serial No. 107,196,
which is a division of application Serial No.
78,990, dated May 11, 1936. Divided and this
application April 13, 1937, Serial No. 136,617

2 Claims. (Cl. 29—148)

This invention relates to methods of making separable slide fastener tapes, and more particularly to a two-part stop for use in detachably holding the ends of a pair of slide fastener tapes together.

In the use of slide fastener tapes of the above nature having rows of cooperating fastener elements along the opposing edges of the tapes, and in which said elements are adapted to be interlocked by the movement of a slide member, it has been found in many instances that the last element of the row at the end of a tape became loosened, and either shifted out of its proper position or was pulled off, resulting in premature separation of the ends of said tape.

One object of this invention is to provide a method of making a two-part stop of the above nature whereby the ends of the tapes will be fitted closely and neatly together in an easy and positive manner.

Another object is to provide a method of making a device of the above nature which, when clamped at the ends of the slide fastener tapes, will prevent the last fastener element from being moved out of position or pulling off.

Still another object is to provide a method of making a detachable stop of the above nature consisting of a pair of cooperating male and female members, each of which is made from a single piece of metal.

A further object of this invention is to provide a method of making the male or pin member of the detachable stop.

A still further object is to provide a method of making a detachable stop of the above nature which will be simple in construction, inexpensive to manufacture, easy to manipulate, compact, ornamental in appearance, and very efficient and durable in use.

With these and other objects in view, there has been illustrated on the accompanying drawings one form in which the invention may be conveniently embodied in practice.

In the drawings:

Fig. 1 illustrates a pair of interlocked fastener element tapes having the improved detachable stop assembled at the lower ends thereof.

Fig. 2 is a fragmentary view of the lower ends of said tapes as they appear when separated.

Fig. 3 is an enlarged front view of the lower ends of the tapes showing the detachable stop members in assembled position.

Fig. 4 is a similar enlarged view of the same taken from the rear.

Fig. 5 is an enlarged edge view taken on the

line 5—5 of Fig. 3 with the tapes removed, looking downwardly.

Fig. 6 is an enlarged bottom edge view of the parts shown in Fig. 3, looking upwardly in the direction of the arrows 6—6.

Fig. 7 is an enlarged side edge view of the male member of the stop.

Fig. 8 is an enlarged side edge view of the female member of the same.

Figs. 9 to 13 inclusive are views showing the 10 appearance of the blank after the successive steps in the method of making the male member of the stop.

This application is a division of a prior application by the same inventors filed October 23, 1936, 15 Serial No. 107,196, entitled "Methods of making two-part stops for separable slide fastener tapes", which application in turn is a division of a prior application filed May 11, 1936, Serial No. 78,990, entitled "Two-part stops for separable slide fas- 20 tener tapes".

Referring now to the drawings in which like reference numerals denote corresponding parts throughout the several views, the fastener element tapes upon the ends of which the detachable 25 male and female members of the improved stop are applied comprise a pair of narrow elongated beaded fabric strips or stringers 10 and 11, each having a row of forked jaw elements 12 clamped upon the beaded edges thereof, and said rows of 30 elements are adapted to be interlocked for connecting the tapes together by the camming action of a tapered slide 13 mounted thereon, when it is pulled upwardly from the lower end thereof, as viewed in Fig. 1. The rows of connected elements 12 are adapted to be disengaged from each other to permit separation of the tapes by moving the slide 13 in the reverse direction, all of which is in accordance with the well known practice in this art.

Each element 12 is provided with a pair of opposed jaws which are crimped inwardly upon the edges of the tapes by suitable clamping tools not shown. The slide 13 is preferably provided with a hinged finger piece 14 to facilitate the manipulation thereof, said slide preferably having a pair of parallel spaced plates 15 and 16 adapted to embrace the rows of elements 12 therebetween. The side plates 15 and 16 are provided on both side edges with inwardly extending side flanges 17 for confining the elements 12 and forcing them together into cooperating engagement.

The detachable male and female members 18 and 19 of the stop forming the present invention are shown in Fig. 1 in assembled position applied 55

to the bottoms of a pair of tapes 10 and 11. Each of the members 18 and 19 is preferably made of one piece of material, such as a blank of sheet metal, formed and attached to the tapes according to the methods to be hereinafter described.

Female stop member

The female member 18 includes a pair of opposed tape-embracing plates 20 and 21 having aligned openings 22 therein which, when the member is attached to the tape, serve to facilitate the attachment of the tape to the edge of the article to be closed. Above the plates 20 and 21 and disposed along the edge of the tape abutting the elements 12, a tubular clip 23 is provided which embraces the tape edge and is securely crimped thereto. The clip 23 extends upwardly from the plates 20 and 21 to a point closely adjacent the last element 12 upon the end of the left-hand tape 10 to which the member 18 is attached, as viewed in Fig. 1. Below the clip 23 and with its axis in alignment with the line of jointure of the two rows of elements 12 on the tape edges, a hollow cylindrical socket 24 is provided. Provision is also made of a pair of slider-guiding ears 25, one of which extends upwardly from each of the plates 20 and 21 on opposite faces of the tape 10.

Male stop member

The male member 19 also has opposing tape-embracing plates 26 and 27, similar to the plates 20 and 21 of the female member, and said plates 26 and 27 are likewise provided with circular openings 28 to facilitate securing the tape 11 to the article to be closed. The plate 26 has an upstanding pointed prong 29 formed on its upper edge, which is adapted to be passed through the tape 11 and then bent over and pressed down upon the rear surface of the plate 27 to secure said plates to the tape 11. The plate 26 has a pair of spaced upwardly directed side plates 30 and 31 extending from its upper edge and adapted to embrace the center edge of the tape 11 for reinforcing the same. The lower left-hand corner 32 of the side plate 31 is preferably disposed beneath the plate 27, as clearly shown in Fig. 4. Provision is also made of a pointed prong 33, formed on the rear edge of the side part 30, which is adapted to pass through the tape 11 and be bent over and pressed down upon the outer surface of the opposite side plate 31 to firmly connect the opposing tape embracing plates 30 and 31. The tubular edge portion 34 connecting the side plates 30 and 31 is curved and inclined outwardly slightly from top to bottom and is extended downwardly from the lower edge of these plates in the form of a cylindrical vertical tongue 35 for cooperative engagement with the socket 24. The tongue 35 is spaced from the lower edges of the plates 26 and 27 by a slot 36 with its axis in alignment with the line of jointure of the interlocking rows of elements 12 on the tape edges above it.

The inclined tubular portion 34 extends above the last element 12 on the tape 11 and is slotted, as at 36, to straddle the same. When in assembled position, the rolled tongue 35 of the male member 19 fits within the socket 24 of the female member 18, thereby detachably connecting the opposing lower ends of the tapes 10 and 11. A slot 37 is provided in the meeting edges of the socket 24 to provide clearance for the side plates 30 and 31 of the male member of the stop. The upper end of the slot 38 is adapted to abut against a shoulder 39 at the bottom of said slot

37 to hold the male and female members 19 and 18 in their relative positions, as shown in Figs. 1, 3 and 4, whereby the rows of elements 12 on the opposing tape edges will be properly interlocked when the slide 13 is moved upwardly.

Method of making the male stop member

The steps in the method of making the male member 19 are illustrated in Figs. 9 to 13, inclusive. Thus, Fig. 9 shows a blank 48 stamped out of sheet metal by the first or blanking operation. The opening 28, the prongs 29 and 33, the slot 36, and a portion 49 from which the tubular tongue 35 is rolled are all blanked out in the first step by suitable shearing tools, not shown. The next operation results in bending down the prongs 29 and 33 at right-angles to the blank 48, as shown in Fig. 10, as by suitable forming tools, not shown. Fig. 11 illustrates the appearance of the blank 48 after the next step wherein the side plates 30 and 31 are bent at right-angles to each other, and the inclined tubular portion 34 and the vertical tongue 35 are partially formed by suitable tools, not shown.

Figs. 12 and 13 show the results of the next operation whereby the side plates 26 and 27 are bent at right-angles to each other and the inclined tubular portion 34 and the tongue 35 are more completely formed by suitable tools, not shown. The tooth-like projections 50 of the tongue 35 are bent inwardly to form a blunt point 51 at the end of the tongue 35 by suitable tools to facilitate its insertion into the socket 24 of the female member 18.

The final appearance of the male stop member 19 is illustrated in Figs. 3 and 4, wherein the plates 26 and 27 and the side plates 30 and 31 embrace the tape 11, and are pressed together firmly against the same by suitable tools, not shown, the prongs 29 and 33 being passed through said tape and bent over into engagement with the plate 27 and the side plate 31 by suitable tools, not shown, respectively. This last step completes the tubular portion 34 and the tongue 35 and also disposes the male member 19 upon the tape end with the lowest element 12 in the slot 36. The forming and shearing tools mentioned above have not been shown on the drawings as it is thought that they would be obvious to any workman skilled in this art from a mere inspection of the drawings.

Operation

In operation, in order to connect the tapes 10 and 11, the slide 13, which is permanently retained on the tape 10, will first be pushed downwardly as far as it will go until it strikes the socket 24 of the female member 18. The tongue 35 of the male member 19 will then be inserted through the plates 15 and 16 of the slide and into the socket 24. The slide 13 will next be pulled upwardly while holding the male member 19 firmly, causing the rows of elements 12 to be securely interlocked together. When connecting the members 18 and 19 of the slide stop, as above described, the male member 19 should be pressed downwardly with sufficient force to insure that the edge of the slot 38 of the side plates 30 and 31 engages against the shoulder 39 of the slot 37 in the member 18, thus positioning the lowest elements 12 on the tapes 10 and 11 properly to be interengaged by the cam slide 13 during its upward movement therealong.

The curved bottom portion 52 connecting the side plates 20 and 21 of the female member 18

serves to protect the lower end of the tape 10 against fraying. Likewise, the curved bottom section 53 connecting the side plates 26 and 27 of the male member 19 also protects the end edge of the tape 11. The clip 23 which is clamped along the edge of the tape 10 stiffens and reinforces said tape at this point and prevents loosening of the lower adjacent element 12. The side plates 30 and 31 of the male member reinforce and stiffen the tape 11 adjacent the lowermost element 12, and the slot 36 prevents the lowermost element 12 on the tape 11 from loosening or becoming dislocated. The prongs 29 and 33 securely maintain the male member 19 in proper position on the tape 11.

While there has been disclosed in this specification one form in which the invention may be embodied and a preferred method of making the same, it is to be understood that this form and method are shown and described for the purpose of illustration only, and that the invention is not to be limited to the specific disclosure, but may be modified and embodied in various forms without departing from its spirit. In short, the invention includes all the modifications and embodiments coming within the scope of the following claims.

Having fully described the invention, what is claimed as new, and for which it is desired to secure Letters Patent, is:

1. The method of making an angular male member of a two-part stop for use on a beaded slide fastener tape, which comprises shearing an angle-shaped blank having an integral upper horizontal arm and an integral lower vertical arm from a flat strip of metal with tape penetrating prongs extending laterally and vertically from the upper and lower arms of said angle-shaped blank respectively, and with the horizontal upper arm provided with a reduced depending tongue-forming projection and a horizontal slot adjacent the upper end thereof to fit about and reinforce the lowermost element on said tape, bending the lower vertical arm along a horizontal median line to form a pair of clamping plates to embrace the lower edge of said tape, bending the upper part of said upper arm along a vertical line to form a pair of bead-embracing members, and forming said projection into a cylindrical tongue for engaging in a socket in a cooperating female member of the two-part stop leaving a vertical slot between it and said clamping plates whereby said male member will be anchored very securely upon said tape.

2. The method of making an angular male member of a two-part stop for use on a beaded slide fastener tape, which comprises shearing an angle-shaped blank having an integral upper horizontal arm and an integral lower vertical arm from a flat strip of metal with the horizontal upper arm provided with a reduced integral depending tongue-forming projection and having a tape-embracing portion extending a substantial distance above the upper terminus of said vertical arm, bending the lower vertical arm along a horizontal median line to form a pair of clamping plates to embrace the lower edge of said tape, bending the integral upper part of said upper arm along a vertical line to form a pair of bead-embracing members, and forming said depending projection into a cylindrical tongue for engaging in a socket on a cooperating female member of the two-part stop leaving a vertical slot between said tongue and said clamping plates, whereby said male member will be anchored very rigidly to said beaded tape.

MAX KISSLING.
ADOLPH KRIEGER.
